INVENTOR

J. Parker Pray
By his Attorney W.C. Witten

UNITED STATES PATENT OFFICE.

J. PARKER PRAY, OF NEW YORK, N. Y.

DESIGN FOR A TOILET-BOTTLE.

SPECIFICATION forming part of Design No. 15,115, dated July 1, 1884.

Application filed March 26, 1884. Term of patent 7 years.

To all whom it may concern:

Be it known that I, J. PARKER PRAY, of New York city, in the State of New York, have invented and produced a new and original Design for Toilet-Bottles, of which the following is a specification, reference being had to the accompanying drawings, which form a part of the same.

My design relates to toilet-bottles; and it consists in the design hereinafter shown and described.

Figure 1 shows a face view of one of the sides of the toilet-bottle. Fig. 2 is a plan view of the bottom of the bottle, and Fig. 3 is a perspective view facing one of the corners.

The toilet-bottle of my design is triangular, as is clearly shown in Fig. 2. It has three

faces, *a*, two of which are shown in Fig. 3. At the corners, and separating these faces, are pillars *b*, which may be fluted, as shown in the drawings. Sloping upward from the top of these pillars, and over the shoulders of the bottle to the neck, are the bands *c*.

What I claim as new, and desire to secure by Letters Patent, is—

The design for a toilet-bottle, consisting of the triangular configuration having faces *a*, pillars *b*, and bands *c*, substantially as shown and described.

J. PARKER PRAY.
